UNITED STATES PATENT OFFICE

BERNARD E. O'HAGAN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed June 23, 1931. Serial No. 546,250.

My invention relates to railway traffic controlling apparatus, and particularly to apparatus of the type involving tripping devices located in the trackway and cooperating with train-carried apparatus to apply the brakes under unsafe traffic conditions in advance.

One feature of my invention is the provision of novel and improved means, located partly on the train and partly in the trackway, for permitting the engineman to clear the trackway tripping device under unsafe traffic conditions in advance, such means also operating to impose a low speed limit on the train as long as the train is traveling under unsafe traffic conditions in advance.

I will describe one form of apparatus embodying my invention, and will then point out the novel features thereof in claims.

20 The accompanying drawing is a diagrammatic view showing one form of apparatus embodying my invention.

Referring to the drawing, the reference characters 6 and 6^a designate the track rails of a railway track along which traffic normally moves in the direction indicated by the arrow. At least one of these rails is divided by insulated joints 7 to form a plurality of successive track sections. In the drawing I have shown only the forward end of one section P, and the rear end of the adjoining section Q, but it is understood that the apparatus located at the junction of these two sections will be repeated at the junction of each two successive track sections involved in the system.

Each track section is provided with the usual track circuit, comprising a source of current connected across the rails at the exit end of the section, and a track relay having a winding connected across the rails at the entrance end of the section. As illustrated in the drawing, the source of current for section P is a transformer 21, and the track relay for section Q is designated by the reference character K. Associated with track relay K is a home relay H having a circuit which includes a front contact 20 of track relay K, and which is also controlled by the track relay or relays for one or more sections in advance of Q.

This circuit is supplied with alternating current from a suitable source, the terminals of which are designated BX and CX.

The track section Q is provided with a tripping device 4, which is controlled by a magnet L in such manner that the tripping device occupies its tripping position when the magnet is deenergized, but is moved to its non-tripping position when magnet L becomes energized. When the tripping device 4 is in its tripping position, it cooperates with a train-carried arm 3, which operates a valve G in a brake controlling pipe E. When the arm 3 is operated by the tripping device 4, the valve G is opened to cause an automatic application of the brakes. When the tripping device 4 is in its non-tripping position, it is out of the path of the train-carried arm 3.

The magnet L is provided with a main circuit which includes front contact 16 of the home relay H, so that when relay H is energized, magnet L is also energized to hold the tripping device 4 in its non-tripping position. Magnet L is provided with a stick circuit which passes from terminal BX, through back contact 17 of track relay K, contact 5 which is closed only when the tripping device is in its non-tripping position, and the winding of magnet L to terminal CX. The apparatus disclosed in the present application is intended for use on railways equipped with multiple unit electric trains, and as is well understood the usual practice is to equip each motor car of such trains with an arm 3 and the braking apparatus controlled thereby. The stick circuit just traced for magnet L is the usual stick circuit provided for railways of this type to keep the tripping device 4 in its non-tripping position as long as any part of a train occupies section Q, and so to prevent the forward cars of a train from tripping the rear cars.

Associated with the magnet L is a clearing relay N, which is normally deenergized, but which may become energized at times from a train-carried source of current, as herein-after explained. When the relay N is energized, an auxiliary clearing circuit for magnet L is closed at contact 18, so that magnet L will then become energized, even though relay

H is deenergized. Relay N is provided with a partial trackway circuit which terminates in two spaced contact rails 8^a and 8^b. This partial circuit is from contact rail 8^a, through 5 back contact 19 of relay H, and winding of relay N to contact rail 8^b. This partial circuit is provided with a low resistance shunt around relay N, which shunt includes front contact 19 of relay H, so that the low resistance shunt is closed when and only when relay H is energized.

Referring now to the train-carried apparatus, this apparatus involves an acknowledging relay A which is controlled by a normally closed push button 14 and by an acknowledgement restoring relay AR. Relay A is provided with a stick circuit which passes from terminal B of a suitable source of current, through front contact 10 of relay A, 10 contact of push button 14, and the winding of relay A to terminal C of the same source of current. The pick-up circuit for relay A is from terminal B, through front contact 13 of relay AR, contact of push button 14, and the winding of relay A to terminal C. As long as relay A is energized, a brake application magnet M is also energized by virtue of a circuit which includes front contact 11 of relay A, which circuit will be obvious from 15 the drawing. When magnet M is energized it closes a valve F in the pipe E, and when the magnet M becomes deenergized, it permits this valve to open and thereby cause an automatic application of the brakes. Magnet M is provided with an auxiliary circuit which includes a contact 15 operated by a speed responsive device D. This contact is closed 20 when and only when the speed of the vehicle is below a safe low value, such, for example, as 15 miles per hour. It follows that as long as the acknowledging relay A is energized, the vehicle may travel at any desired speed, but that when this relay becomes deenergized the brakes will be applied if the speed exceeds 25 15 miles per hour.

The restoring relay AR is included in a partial train-carried circuit which terminates in two shoes 9^a and 9^b, arranged to register respectively with the two contact rails 8^a and 8^b. As here shown, the shoes are normally retracted from positions for engagement with the contact rails, but are projected into engaging positions with these rails whenever the acknowledging relay A is deenergized. This may be accomplished by mounting the shoes 9^a and 9^b on a crosshead 23, which is controlled by a pneumatic motor S. The piston 24 of this motor is biased by a spring 22 to an upper position wherein the shoes are in their non-engaging positions. When fluid pressure is admitted to the motor S above the piston 24, however, this piston and the crosshead 23 are moved downwardly against the action of the spring 22 to such 30 position that the shoes will engage with the

trackway contact rails. The supply of fluid pressure to the motor S is controlled by a valve T, and this valve is provided with an operating circuit which includes a back contact 12 of relay A.

The operation of the apparatus is as follows: Assuming that traffic conditions in advance of section Q and up to the control limit of relay H are clear, the tripping device 4 will be in its non-tripping position, so that this device will have no effect on the train-carried apparatus and the train may pass the tripping device at any desired speed.

If track conditions between section Q and the control limit of relay H are not clear, however, home relay H will be deenergized, so that magnet L will be deenergized and the tripping device 4 will be in the tripping position. As the train approaches this tripping device, the engineman may operate the acknowledging push button 14, thereby de-energizing the acknowledging relay A, and this will place the brake application magnet M under the control of speed governor contact 15, so that the train will incur an automatic application of the brakes if the safe low speed limit is exceeded. Back contact 12 of relay A will then close the circuit for valve T, so that the motor S will be operated to project the shoes 9^a and 9^b into positions for engagement with the contact rails 8^a and 8^b, respectively. When these shoes and rails engage, a circuit will be closed, which circuit is from terminal B on the train, through back contact 12 of relay A, winding of relay AR, contact shoe 9^b, contact rail 8^b, winding of relay N, back contact 19 of relay H, contact rail 8^a, and contact shoe 9^a to terminal C of the same source of current. The characteristics of relays AR and N are such that when 35 this circuit is closed relay N will become energized, but relay AR will not. The closing of relay N will energize magnet L, and this in turn will move the tripping device 4 to its non-tripping position, so that the train may proceed into section Q. It is understood that track relay K will open before the contact shoes 9 leave the contact rails 8, so that the auxiliary circuit for magnet L through back contact 17 will be closed before contact 18 of relay N opens. The train may now proceed through section Q, subject, however, to the speed limit imposed by contact 15 of the speed responsive device D. If the next tripping device is in the tripping position, it will be automatically cleared by the cooperation of the train-carried shoes 9 with the trackway contact rails 8 associated with such tripping device. When the train enters a track section the home relay H for which is closed, the low resistance shunt around the associated clearing relay N will be closed, whereupon the current which will then be supplied to train-carried relay AR will be sufficient to close this relay, with the result 40 45 50 55 60 65 70 75 80 85 90 95 100 105 110 115 120 125 130

that the pick-up circuit for the acknowledging relay A will then be closed. The closing of relay A will close the stick circuit for this relay and will remove the low speed limit.

5 It will also deenergize valve T, so that the crosshead 23 and the shoes 9 will be retracted. The train may then proceed at full speed until it again encounters a tripping device in the tripping position.

10 The only reason for moving the contact shoes into and out of positions for engagement with the contact rails 8 is to prevent excessive wear on these parts when a train is passing clear signals.

15 If the shoes and contact rails are constructed in such manner as to withstand actual contact at full speed, the motor S and valve T can be omitted and the shoes can be mounted in such positions as to register with the contact rails at each location.

20 Although I have herein shown and described only one form of apparatus embodying my invention, it is understood that various changes and modifications may be made therein within the scope of the appended claims without departing from the spirit and scope of my invention.

Having thus described my invention, what I claim is:

30 1. Railway traffic controlling apparatus comprising a trackway tripping device, a home relay for controlling said device, a clearing relay for controlling said device, a partial trackway circuit for said clearing relay including a back contact of said home relay and terminating in two spaced contact rails, said partial circuit being provided with a low resistance shunt around the clearing relay including a front contact of said home relay, a train-carried acknowledging relay, a train-carried acknowledgment restoring relay, a stick circuit for said acknowledging relay including a normally closed acknowledging push button, a pick-up circuit for said acknowledging relay including said push button and a front contact of said restoring relay, a partial train-carried circuit terminating in two shoes which register with said two contact rails respectively and including a source of current and a back contact of said acknowledging relay as well as the winding of said restoring relay, said partial circuits being so proportioned that when the shoes engage the contact rails the clearing relay will close when the low resistance shunt is open but the restoring relay will not close unless said shunt is closed, and brake controlling apparatus on the train controlled by said tripping device and by said acknowledging relay.

35 2. Railway traffic controlling apparatus comprising a trackway tripping device, a home relay for controlling said device, a clearing relay for controlling said device, a partial trackway circuit for said clearing

relay including a back contact of said home relay and terminating in two spaced contact rails, said partial circuit being provided with a low resistance shunt around the clearing relay including a front contact of said home relay, a train carried acknowledging relay, a train-carried acknowledgment restoring relay, a stick circuit for said acknowledging relay including a normally closed acknowledging push button, a pick-up circuit for said acknowledging relay including said push button and a front contact of said restoring relay, a partial train-carried circuit terminating in two shoes which register with said two contact rails respectively and including a source of current and a back contact of said acknowledging relay as well as the winding of said restoring relay, said partial circuits being so proportioned that when the shoes engage the contact rails the clearing relay will close when the low resistance shunt is open but the restoring relay will not close unless said shunt is closed, and brake controlling apparatus on the train controlled by said tripping device and by said acknowledging relay.

40 3. Railway traffic controlling apparatus comprising a trackway tripping device, a home relay for controlling said device, a clearing relay for controlling said device, a partial trackway circuit for said clearing relay including a back contact of said home relay and terminating in two spaced contact rails, said partial circuit being provided with a low resistance shunt around the clearing relay including a front contact of said home relay, a train-carried acknowledging relay, a train-carried acknowledgment restoring relay, a stick circuit for said acknowledging relay including said push button and a front contact of said restoring relay, a partial train-carried circuit terminating in two shoes which register with said two contact rails respectively and including a source of current and a back contact of said acknowledging relay as well as the winding of said restoring relay, said shoes being normally retracted from positions for engagement with said rails, means operating when said acknowledging relay is open to project said shoes into positions for engagement with said rails, said partial circuits being so proportioned that when the shoes engage the contact rails the clearing relay will close when said low resistance shunt is open but the restoring relay will not close unless said shunt is closed, and brake controlling apparatus on the train controlled by said tripping device and by said acknowledging relay.

45 4. Railway traffic controlling apparatus comprising a trackway tripping device, a

home relay for controlling said device, a clearing relay for controlling said device, a partial trackway circuit for said clearing relay including a back contact of said home relay and terminating in two spaced contact rails, said partial circuit being provided with a low resistance shunt around the clearing relay including a front contact of said home relay, a train-carried acknowledging relay, a 10 train-carried acknowledgment restoring relay for controlling said acknowledging relay, a partial train-carried circuit terminating in two shoes which register with said two contact rails respectively and including a source 15 of current and the winding of said restoring relay, said partial circuits being so proportioned that when the shoes engage the contact rails the clearing relay will close when said low resistance shunt is open but the restoring relay will not close unless said shunt is closed, and brake controlling apparatus on the train controlled by said tripping device and by said acknowledging relay.

25 In testimony whereof I affix my signature.
BERNARD E. O'HAGAN.
